CLAIM

(21) Appl. No.: **29/133,994**

The ornamental design of a flexible hydraulic brake line assembly for a motor vehicle, as shown and described.

(22) Filed: **Dec. 18, 2000**

DESCRIPTION

(51) LOC (7) Cl. **12-16**

FIG. 1 is a perspective view of a flexible hydraulic brake line assembly for a motor vehicle showing my new design; FIG. 2 is a side view thereof; and, FIG. 3 is an end view thereof, the opposite end view being the same.

(52) U.S. Cl. **D12/180**

The portions broken away are for disclosing indeterminate length.
